CLAIM

The ornamental design for a pacifier box, as shown and described.

DESCRIPTION

FIG. 1 is a perspective view of pacifier box, showing our design;

FIG. 2 is a front view thereof;

FIG. 3 is a right view thereof;

FIG. 4 is a left view thereof;

FIG. 5 is a top view thereof;

FIG. 6 is a bottom view thereof; and,

FIG. 7 is a back view thereof.

The broken lines in the drawings depict portions of the pacifier box which form no part of the claimed design.
